UNITED STATES PATENT OFFICE

ARTHUR G. SMITH, OF LONG BEACH, CALIFORNIA

CABINET-LID CONSTRUCTION

Application filed October 15, 1928. Serial No. 312,585.

This invention relates to improvements in brace constructions for hinged closures.

An object of the invention is to provide a brace construction for hinged closures which may be employed in a variety of different circumstances and which connects the hinged closure and the stationary structure on which the closure and the stationary structure on which the closure is mounted serving to hold the closure in open position when opened. Under many circumstances it is highly desirable to be able to move a hinged closure from closed position to open position or partially open position and to have a construction which will automatically cause the closure to remain in open position against the action of gravity or against the action of springs which may be employed, urging the closure into closed position.

20 Another object of the invention is to provide a construction for accomplishing the above mentioned results which is of simple, cheap and durable construction and which requires no care or attention.

25 Another object of the invention is to provide a brace construction for hinged closures which will permit the closure to be moved into a partially open position and automatically prevent closing movement of the closure
30 from the partially open position until the closure has been moved to fully opened position.

Another object of the invention is to provide a brace construction having the above mentioned characteristics, which is capable of being manually operated to permit closing of the closure without moving the closure into a fully opened position.

With the foregoing and other objects in view which will be made manifest in the following detailed description and specifically pointed out in the appended claims, reference is had to the accompanying drawings for an illustrative embodiment of the invention, wherein:—

Fig. 1 is a view in vertical section through a portion of a cabinet having a hinged closure to which the construction embodying the invention has been applied, the closure being shown in closed position.

Fig. 2 is a partial view in vertical section of the construction shown in Fig. 1 illustrating the position of the parts during opening movement of the closure.

Fig. 3 is a view similar to Fig. 2 illustrating the position of the parts wherein closing movement of the closure is prevented by the improved brace construction. 55

Fig. 4 is a view similar to Fig. 2 illustrating the position of the parts when the closure is in fully opened position.

Fig. 5 is a partial view in horizontal section taken substantially upon the line 5—5 upon Fig. 3.

Fig. 6 is a vertical section taken substantially upon line 6-6 upon Fig. 4. 65

Fig. 7 is a vertical section taken upon the line 7-7 upon Fig. 2.

Referring to the accompanying drawings wherein similar reference characters designate similar parts throughout, the improved brace construction may be used in conjunction with hinged closures such as are employed on phonographs, radio cabinets, desks, and even upon closures employed in automobile bodies. In short the construction may be employed wherever a hinged closure is employed which closure is urged into closed position either by gravity or by springs. In illustrating the invention, however, the brace construction is shown as having been mounted upon a cabinet C having a hinged closure L hingedly mounted upon the cabinet as by hinges H. The brace construction consists of a brace 10 preferably cylindrical in form and in the form of a short steel rod which is of such length that it may support the closure in any open position. This brace is pivotally mounted upon a bracket 11

brace is pivotally mounted upon a bracket 11 which is fastened as by screws 12 to the under side of the closure L. The brace 10 is provided near its upper end with an adjustable collar 13 which may be held in adjusted position by means of a set screw 14. The lower end of the brace is upset or enlarged as indicated at 15 thus forming an abutment at the lower end of the brace corresponding to the abutment provided at the upper end of the brace by the collar 13. The bracket 11 and brace 10 are disposed near a side edge of the

closure so that the brace will be close to the inside surface of the wall W on the cabinet. A member generally designated by the reference character 16 is pivotally mounted on the inside surface of the wall W as by a screw 17. A washer 18 is preferably arranged on the screw between the member 16 and the wall W so that the member may freely pivot on the screw. This member consists of a back plate 19 which is somewhat triangular shape and has top and bottom flanges 20 and 21 projecting outwardly from its top and bottom edges. The bottom flange 21 has an aperture 22 formed therein which is of substantially the same size as the diameter of the brace 10 or slightly larger. The top flange 20 has an elongated aperture 23 formed therein. The outer side of this aperture is provided with an inwardly extending projection 24 which is somewhat rounded and serves to define the aperture 23 into a forward end indicated at 25 and an elongated rear end 26. The forward end 25 of the aperture 23 is slightly larger than the diameter of the brace 10 and this portion of the aperture 23 is in alignment with the aperture 22. The rear end 26 is elongated and may be considered as being offset with respect to the aperture 22. A leaf spring 27 shown as being angular in form is fastened against the back plate 19 by a hollow rivet 27^a. This spring has its upper end widened so that it is substantially as long as the complete length of the aperture 23. The upper end of the spring bears against the brace 10, urging it outwardly against the outer side of the aperture 23 on which the projection 24 is formed. In the preferred form of construction the top flange 21 is extended forwardly to provide a handle 28.

The operation of the device is as follows: When the closure L is in closed position the pivoted member 16 is in its lowermost position with the brace 10 disposed in the rear end 26 of the aperture 23 and extending through the aperture 22. When it is desired to open the cabinet the closure L is grasped and manually lifted and during this movement the brace 10 slides freely upwardly through the aperture 22 and through the rear end 26 of aperture 23 as shown in Fig. 2. When the closure is in partially open position it may be released and on starting its downward movement under the influence of gravity or of springs which may be present, the action of gravity on the pivoted member 16 together with its frictional engagement with the brace 10 will move it from the position shown in Fig. 2 to the position shown in Fig. 3. By virtue of the fact that the rear end 26 of the aperture 23 is elongated the brace 10 can freely move through this end of the aperture. Downward movement of the pivoted member, however, causes it to bind on the brace 10 in the aperture 22, thus preventing further

closing movement of the closure. In this manner it will be appreciated that the closure L can be swung into any partially open position and on being released in such position it will be held there by means of the brace which acts automatically. If it is desired to further open the closure it is manually lifted and upward movement of the brace 10 swings the pivoted member 16 from the position shown in Fig. 3 to the position shown in Fig. 2 permitting the brace to freely slide through the pivoted member. On again releasing the closure L the pivoted member will again swing into its lowermost position, binding on the brace 10 and holding the closure open.

When it is desired to close or lower closure L this may be accomplished as follows: The closure L is grasped and lifted into fully opened position or into the position shown in Fig. 4. Upward movement of the closure lifts the brace 10 causing the enlargement 15 to engage the bottom flange 21 on the pivoted member 16, swinging the pivoted member upwardly. During the upward swinging of the pivoted member the brace 10 moves forwardly in the aperture 23 until it engages the projection 24. On engaging the projection 24 it rides over this projection or is sprung over it against the action of the angular spring 27. The aperture 22 may be widened slightly laterally to permit this slight lateral movement. After passing over the projection 24 the spring urging the brace 10 outwardly keeps it at the forward end 25 of the aperture 23. When in this position the spring 27 and the projection 24 cooperates in keeping the brace and pivoted member in such relation that the brace will always be in alignment with the aperture 22. When in this position the brace 10 can freely slide downwardly through the pivoted member without binding, enabling the closure L to be closed. On reaching the closed position the collar 13 engages the top flange 20, urging the pivoted member downwardly causing the projection 24 to press against the brace 10 with sufficient force to cause the brace to ride over the projection against the action of the spring 27 into the rear end 26 of the aperture 23. After having returned to this position on again opening the closure L the brace 10 will freely slide upwardly through the pivoted member but will bind on starting to move in a downward direction when the closure is released.

In order to close the closure L without moving it into its fully opened position the handle 28 on the pivoted member can be manually lifted, thus swinging the pivoted member 16 and accomplishing the same result accomplished by the enlargement 15 engaging flange 21. As soon as that pivoted member is thus manually shifted the closure can be lowered and the collar 13 will engage the top flange 20 returning the pivoted member to its initial position.

From the above described construction it will be appreciated that a novel brace construction for hinged closures is provided which is highly advantageous in that it will hold the closure open in any position. Furthermore the action of the brace construction is automatic except when it is desired to lower the closure from partially opened position without first moving it into fully opened position. The device is so constructed that it needs no attention whatsoever, during normal operation. Under most circumstances a single brace is used upon a closure but if desired two braces may be employed, one located near each side edge of the closure. The improved brace is highly advantageous when thus employed by virtue of the fact that there are no notches on the brace which must be engaged by a keeper or latch as in many conventional constructions, therefore it is not necessary that the parts of the two brace constructions employed be mounted in exactly corresponding positions on the opposite sides of the cabinet.

Various changes may be made in the details of construction without departing from the spirit or scope of the invention as defined by the appended claims.

I claim:

1. A brace construction for hinged closures comprising a brace, means for pivotally mounting the brace upon a hinged closure, a pivoted member adapted to be pivotally mounted on a stationary structure adjacent the hinged closure, said pivoted member having top and bottom flanges arranged on opposite sides of the pivot, there being apertures formed in the flanges through which the brace extends, the aperture in one of said flanges being of such a size that it may bind upon the brace, the other aperture being of such size that the brace may move therein into a position wherein it will bind in the first aperture when movement is attempted therethrough in one direction, or into a second position wherein the brace may move through the first aperture in either direction, and means for maintaining the brace in either position in the second aperture.
2. A brace construction for hinged closures comprising a brace, means for pivotally mounting the brace upon a hinged closure, a pivoted member adapted to be pivotally mounted on a stationary structure adjacent the hinged closure, said pivoted member having top and bottom flanges arranged on opposite sides of the pivot, there being apertures formed in the flanges through which the brace extends, the aperture in one of said flanges being of such a size that it may bind upon the brace, the other aperture being of such a size that the brace may move therein into a position wherein it will bind in the first aperture when movement is attempted therethrough in one direction, or into a second position wherein the brace may move through the first aperture in either direction, and means for maintaining the brace in either position in the second aperture.

ond position wherein the brace may move through the first aperture in either direction, and means for maintaining the brace in either position in the second aperture, there being a projection formed on the side of the second mentioned aperture, and spring means urging said brace against said side whereby the brace may be maintained in either of the positions in the second mentioned aperture.

3. A brace construction for hinged closures comprising a brace, means for pivotally mounting the brace upon a hinged closure, a pivoted member adapted to be pivotally mounted on a stationary structure adjacent the hinged closure, said pivoted member having top and bottom flanges arranged on opposite sides of the pivot, there being apertures formed in the flanges through which the brace extends, the aperture in one of said flanges being of such a size that it may bind upon the brace, the other aperture being of such size that the brace may move therein into a position wherein it will bind in the first aperture when movement is attempted therethrough in one direction, or into a second position wherein the brace may move through the first aperture in either direction, and means upon the brace engageable upon the flanges for moving the pivoted member into either of the two relative positions with respect to the brace, and means for maintaining the pivoted member in either of the positions.

4. A brace construction for hinged closures comprising a brace, means for pivotally mounting the brace upon a hinged closure, a flanged pivoted member adapted to be pivotally mounted upon a stationary structure adjacent the hinged closure, said pivoted member having an elongated opening in its flange through which the brace slidably extends, means dividing the opening into two defined ends, one of which is larger than the other, the brace being adapted to bind on the pivoted member when in the smaller end of the opening and to slide freely through the opening when disposed in the large end, and means for urging the brace to remain in either end of the opening but permitting it to be moved from one end to the other.

In testimony whereof I have signed my name to this specification.
